SPIRAL TUBE WINDING MACHINE

Henry De Smith, Rochester, N. Y., assignor to
M. D. Knowlton Company, Rochester, N. Y., a
corporation of New York

Application June 2, 1938, Serial No. 211,409

12 Claims. (Cl. 93—80)

This invention relates to machines for winding spiral paper tubes and the like.

In the making of paper tubes, a plurality of strips of paper with adhesive thereon, are spirally wound on a mandrel to form the tube. Where a tube having a heavy wall is to be wound, it is necessary to build up such a tube from many strips or plies of paper customarily applied in sets, each set being applied by a separate winding head. Such a winding head includes a winding belt which compresses the several sets of paper strips, suitably coated with adhesive, into a compact tubular layer. In the manufacture of such a thick walled tube by using two winding heads, the belt of the first head engages the top ply of half the number of plies and the belt of the second winding head in succession engages the outside ply of the remaining strips comprising the tube. In the case where more than two winding heads are used, for example, three or four, the number of plies under the belt of each head will be of approximately equal thickness. If the winding belts of a multi-unit winder run at the same speed, successive belts will engage tube sections of different diameters and will run slower than the tube sections with the result that the speed of preceding belts will be counteracted and a loosely wound, unsatisfactory tube will result. In the past it has been necessary to interchange pulleys on the winding heads to bring their winding belts into proper speed relation for the forming of compactly wound tubes. However, such a procedure is cumbersome and unsatisfactory.

The present invention has for its purpose a novel arrangement whereby the belts on the winding heads of a multi-unit spiral-tube winder can be easily and accurately adjusted to operate at such a speed that all of the paper layers will be uniformly wound into a compactly formed tube. The various features and advantages of the invention will appear from the detailed description and claims when taken with the drawings in which Fig. 1 is a front elevation of the winder of the present invention; Fig. 2 is a plan view of the winder of Fig. 1 showing the manner of feeding the paper strips thereto, and

Fig. 3 is a skeleton showing of the driving and adjusting elements of the winder. The spiral tube 5 to be made on the present machine is formed from a plurality of strips or plies of paper herein designated 6, 7 and 8 suitably coated with adhesive on certain of their surfaces and wound into spiral form to constitute the finished tube. The machine on which the

tube 5 is wound comprises a frame 9 provided with a bed plate 10, and a fixed horizontal mandrel 11 on which the layers or plies of paper are spirally wound by means hereinafter described.

In the present machine two winding heads in aligned relation generally designated 12 and 13 are disclosed, although it will be understood that additional winding heads may be utilized where spiral tubes of greater thickness are desired. Each winding head comprises a saddle 14 adjustably mounted on the bed plate on which saddle there is provided a slide 15 mounted to swivel on the saddle. The slide 15 is adjusted by means of the fixed gear segment 16 forming a part of the saddle and a worm gear (not shown) journaled in the slide and in engagement with the segment. The worm gear is rotated by means of the handwheel 17. On this slide there are mounted two vertical shafts 18 and 19 in spaced relation. These shafts support pulleys 20 and 21 about which a twisted belt 22 passes around the mandrel 11 in engagement with the top ply of a set of plies to be formed into the paper tube. The shaft 18 is fixed relative to the slide and is driven by means to be described. However, the shaft 19 which carries the pulley 21 (preferably driven) is mounted in a bracket 23 adjustable relative to the fixed shaft 18 along the slide 15, by means of the screw 24 operated by the hand-wheel 25 so that shaft 19 and the pulley 21 thereon can be adjusted with respect to the pulley 20. By adjusting the pulley 21 with respect to the pulley 20, the twisted belt 22 which is wrapped around the mandrel as indicated at 26 can be tightened or loosened to effect the desired compression and travel of the several plies of paper into tubular form on the mandrel 11. It will be understood that the mandrel 11 is detachably supported in the adjustable clamps 27 and may be replaced by a mandrel of any wanted size.

Since the winding heads 12 and 13 as well as the driving mechanism related thereto are substantially identical, like reference characters, with the addition of the letter *a*, have been used to indicate the elements associated with the winding head 13, which correspond to similar elements associated with the winding head 12.

The pulley shaft 18 of the winding head 12 carries a beveled gear 28 (Fig. 3), driven by the beveled pinion gear 29 which is mounted on the shaft 30. Shaft 30 extends longitudinally of the frame and is journaled in suitable bearings 31 carried by the bed plate 10. One end of the shaft 30 is provided with a grooved pulley 32 which is driven by means of the belts 33 in turn driven

by the grooved pulley 34 on the variable-speed shaft 35 of the variable-speed transmission unit indicated generally by 36.

The transmission unit 36 includes the parallel shafts 35 and 37 on which there are mounted split conical pulleys 38. These pulleys are engaged by the respective margins of a V-type belt 39 and may be adjusted through the levers 40, shiftable by means of the screw 41, for moving the respective halves of each pulley toward or away from each other to vary the speed ratio of the respective pulleys. It will be seen that by rotating the adjusting screw 41, by means of the handwheel 42, the ends of the levers 40, which are pivoted on the nuts 43 carried by the adjusting screw, can be moved toward or away from each other. This adjustment of these levers will swing them about their individual pins 44 carried by the frame of the transmission unit 36, to move the respective halves of one pulley closer together and the respective halves of the other pulley farther apart so that the effective diameters of these pulleys will be changed.

While a certain type of transmission unit has been illustrated and described, various other types of units, such as two interengaging tapered pulleys may likewise be used.

The fixed speed shaft 37 of the transmission unit 36 carries a grooved pulley 45 driven by the belts 46 in turn driven by the grooved pulley 47 mounted on the shaft of the motor 48. The pulley 45 is provided with a clutch 49 operated by means of the safety shifting lever 50 so that the machine may be instantly started or stopped.

The pulley shaft 18a of the winding head 13 carries a beveled gear 28a driven by the beveled pinion gear 29a which is mounted on the shaft 30a. The shaft 30a which is separate from the shaft 30 is mounted in alignment therewith and is journaled in suitable bearings 31a carried by the bed plate. The righthand end of the shaft 30a is provided with a grooved pulley 32a which is driven by means of the belts 33a. These belts are driven by the grooved pulley 34a on the variable speed shaft 35a of the variable speed transmission unit generally designated 36a. The fixed speed shafts 37a of this unit, is coupled to the fixed speed shaft 37 through the extension shaft 51 and the couplings 52 so that these shafts operate at the same rate of speed.

The adjusting screw 41a for the variable speed transmission unit 36a, is mounted in alignment with the corresponding adjusting screw 41 of the variable speed transmission unit 36. These screws are arranged to be adjusted either independently or as a unit, and to effect this result these screws are connected together by means of a coupling shaft extension 53 and a cutout clutch 54. When this cutout clutch is in full engagement, the adjusting screws 41 and 41a are connected through the extension shaft 53 so that an adjustment of either of the handwheels 42 or 42a, respectively mounted on these screws, will similarly effect the winding speed at both winding heads 12 and 13 simultaneously, thereby keeping the speed between the winding heads at a predetermined proportion. However, if it is desired to increase the speed of the second winding head 13 independently of the winding head 12, the clutch shifter 55 is moved to a position so that the screw 41a is disengaged from the shaft extension 53. Under this condition when the handwheel 42a is rotated, the speed transmission unit 36a only will be effected and it

may be adjusted to increase or decrease the speed of the belt 22a on the winding head 13.

In making a spiral paper tube on the above described machine, a dry paper strip 6 is fed from a reel stand 56 (Fig. 2) at one side of the winding head to form the first or inner ply of the tube. A plurality of paper strips 7 are next fed to the machine from the other side of the winding head and these strips with the exception of the uppermost one, are preferably coated with adhesive on both surfaces thereof, in a glue tank 57. The surface 58 of the uppermost strip 7 is uncoated to prevent the adhesive on the inner plies from coming in contact with the winding belt 22 of the winding head 12. The winding belt 22 snugly encircles the spirally wound plies 6 and 7 and compresses them about the mandrel while at the same time automatically feeding the tube toward the right, as viewed in Fig. 2. The set of paper strips 8 are applied to the partially completed tube by the winding head 13 in the same manner as the strips 7, the upper surface of the outer ply 59 being left uncoated in order to keep the winding belt 22a of the winding head 13 free of adhesive. The finished paper tube 5 as it leaves the mandrel 11 can be fed to a suitable cutoff unit (not shown) where it is severed into pieces of desired lengths.

It will be seen that if the several winding belts 22 and 22a were to run at the same speed, the finished paper tube would be of loose, unsatisfactory construction for the outside diameter of the paper tube at each of the winding heads is different, since a number of plies of paper are applied to the moving tube just before it enters a winding head. Thus for example the winding belt 22a of the head 13 would tend to slow up the other winding belt 22 resulting in a loosely wound tube.

It will thus be seen that the winder of the present invention can be readily set up to wind tubes of any diameter merely by introducing the appropriate mandrel therein and by adjusting the speed of the winding head or heads without the cumbersome operation of changing driving pulleys to obtain the required speed or speeds. Furthermore, the ease in effecting the change of speed in the several winding heads uniformly produces a more satisfactory product.

What I claim is:

1. A machine for winding spiral tubes comprising a mandrel, a plurality of winding heads disposed in operative relation to said mandrel, means for driving said winding heads at predetermined speeds, said means including a variable speed transmission unit for one of said heads, and means for adjusting said transmission unit to vary the speed of said last-mentioned head with relation to the speed of another of said winding heads.

2. A machine for winding spiral tubes comprising a frame, a mandrel supported on said frame, a plurality of winding heads carried by said frame, separate means for driving each of said winding heads, said means including a variable speed transmission unit for each of said winding heads, and means for adjusting each of said transmission units to vary the speed of said winding heads.

3. A machine for winding spiral tubes comprising a frame, a mandrel supported on said frame, a pair of pulleys mounted for rotation on said frame, a belt carried by said pulleys and twisted about said mandrel, means for driving

- at least one of said pulleys, said means including a variable speed transmission unit, a member for adjusting said transmission unit to vary the speed of rotation of the pulley driven thereby, a second pair of pulleys mounted for rotation on said frame, a belt carried by said second pair of pulleys and twisted about said mandrel, and means for driving at least one pulley of said second pair. 5
10. 4. A machine for winding spiral tubes comprising a frame, a mandrel supported on said frame, a pair of pulleys mounted for rotation on said frame, a belt carried by said pulleys and twisted about said mandrel, means for driving at least one of said pulleys, said means including a variable speed transmission unit, a member for adjusting said transmission unit to vary the speed of rotation of the pulley driven thereby, a second pair of pulleys mounted for rotation 10 on said frame, a belt carried by said second pair of pulleys and twisted about said mandrel, means for driving at least one pulley of said second pair, said means including a second variable speed transmission unit, a member for adjusting said unit for varying the speed of rotation of the last-mentioned pulley, and means for selectively coupling said members to adjust said transmission units simultaneously. 15
15. 5. A machine for winding spiral tubes comprising a frame, a mandrel supported on said frame, a plurality of winding heads carried by said frame, means for driving said winding heads, said means including a plurality of variable speed transmission units each having a fixed 20 speed shaft and a variable speed shaft, means for transmitting the rotation of the variable speed shaft of each transmission unit to a winding head, means for adjusting the speed of said variable speed shafts, and means for selectively or simultaneously operating said last-mentioned 25 means. 30
20. 6. A machine for winding spiral tubes comprising a frame, a mandrel supported on said frame, a plurality of winding heads carried by said frame, means for driving said winding heads, said means including a plurality of variable speed transmission units each having a fixed speed shaft and a variable speed shaft, means for transmitting the rotation of the variable speed shaft of each transmission unit to a winding head, means for adjusting each of said transmission units to vary the speed of the variable speed shafts, a shaft interconnecting said last-mentioned means for simultaneously adjusting the speed of said variable speed shafts, a clutch on said shaft whereby said variable speed shafts may be separately adjusted on disengagement of said clutch. 35
25. 7. A machine for winding spiral tubes or the like comprising a mandrel, a plurality of winding heads, each winding head including a belt twisted about said mandrel, individual driving means for each of said winding heads, said means each including a variable speed transmission unit having a driven shaft and a variable speed shaft, a split-cone pulley on each shaft, a belt connecting said pulleys, means including a lever for regulating the spacing between the respective halves of the split-cone pulleys and thereby adjust the speed of said variable speed shaft, a screw for shifting said lever, means for driving said driven shafts at the same rate of 40 speed, and means for selectively coupling the screws of the transmission units to simultaneously adjust the speed of each variable speed shaft. 5
30. 8. A machine for winding spiral tubes comprising a frame, a mandrel supported thereon, a plurality of winding heads carried by said frame, means for driving one of said winding heads, said means including a variable speed transmission unit, means for adjusting said variable speed transmission unit to control the speed of the winding head driven thereby, said last-mentioned means including a lever and a screw for shifting said lever, means for driving another of said winding heads, said means including a variable speed transmission unit, means for adjusting said last-mentioned transmission unit including a lever and a screw for moving said lever, and means for coupling said screws whereby said levers may be shifted simultaneously. 10
35. 9. A machine for winding spiral tubes or the like, comprising a mandrel, a plurality of winding heads, each winding head including a belt twisted about said mandrel, means individual to each of said winding heads for driving said belts at predetermined speeds, said means each comprising a variable speed transmission unit having a fixed speed-shaft and a variable speed shaft, a split-cone pulley on each shaft, a belt connecting said pulleys, a lever for shifting the respective halves of said pulleys and thereby adjust the speed of said variable speed shaft, a screw for shifting the lever, means coupling said fixed speed shafts together, a coupling shaft extending between the screws of each transmission unit whereby said levers may be shifted simultaneously on rotation of a screw, and a clutch for disengaging said coupling shaft. 15
40. 10. A machine for winding spiral tubes or the like comprising a mandrel, a plurality of winding heads disposed in operative relation to said mandrel, a plurality of transmission units, each transmission unit having a driven shaft and a variable speed shaft, a split-cone pulley mounted on each shaft, a belt connecting said pulleys, a pair of levers for shifting the respective halves of said pulleys to vary the effective diameter thereof and thereby adjust the speed of said variable speed shaft, a screw for simultaneously shifting said levers, means for coupling said driven shafts together, means for selectively coupling the screws of the several transmission units to simultaneously adjust the speed of each variable speed shaft, and means for transmitting the rotation of each variable speed shaft to a related winding head. 20
45. 11. A machine for winding spiral tubes comprising a mandrel, a plurality of winding heads disposed in operative relation to said mandrel, means for driving said winding heads, and means for adjusting the speed of one of said winding heads with relation to the speed of another of said winding heads. 25
50. 12. A machine for winding spiral tubes comprising a mandrel, a plurality of winding heads disposed in operative relation to said mandrel, separate means for driving each of said winding heads, said means being adjustable to vary the speed of said heads, and means for selectively or simultaneously adjusting said means to vary the speed of said heads. 30

HENRY DE SMITH.
